(57) **CLAIM**

I claim the ornamental design for a bracelet for holding graphical displays, as shown and described.

DESCRIPTION

FIG. 1 is a perspective view of a bracelet for holding graphical displays showing my new design;

FIG. 2 is a top plan view;

FIG. 3 is a bottom plan view;

FIG. 4 is a side elevational view;

FIG. 5 is an end elevational view; and,

FIG. 6 is another end elevational view.
